Amos H. Johnson

UNITED STATES PATENT OFFICE

DANIEL F. DALTON, OF WATERBURY, CONNECTICUT, ASSIGNOR TO THE SHOE HARDWARE COMPANY, OF WATERBURY, CONNECTICUT, A CORPORATION OF CONNECTICUT

FASTENING DEVICE

Application filed October 14, 1925. Serial No. 62,348.

This invention relates to multiple fastening devices using a series of interengageable elements.

Usually the elements on one side of such a device carry projections which engage a suitable recess of the members of the opposite side, said projections and recesses being placed directly between the anchoring portions of their respective elements. This necessitates a wide and bulky fastening device occupying a comparatively large space especially where it is used as a shoe fastener. Another objection to having the projections or hooks, in the particular case cited, placed in the same plane with the anchoring portions of their respective elements is the tendency for said projections to become entangled with outside objects when the fastening device is open. This might result in bending or otherwise distorting the hooks and thereby making the fastener inoperative. The object of my invention is to overcome the aforementioned objections and to produce a multiple fastening device which is more compact in form and less apt to become inoperative when not in use.

For a detailed description of a preferred form of my invention, reference may be had to the following specification and to the accompanying drawings forming a part thereof, in which:

Fig. 1 is a plan view of the multiple fastening device;

Fig. 2 is a sectional view taken on the

line A—A of Figure 1;

Fig. 3 is a bottom plan view on an enlarged scale of the fastener partly in section showing the members of the opposite sides in an interengaged position;

Fig. 4 is a sectional view of the slider.

Referring to the drawings, a multiple fastener is shown comprising a pair of fabric stringers 1 which may be of any desired material but are preferably formed of square woven fabric folded about a cord or other flexible member 2 to afford a good grip for the metallic elements in which this invention is particularly concerned. Two series of elements 3 and 4 are preferably employed, the former comprising anchoring portions 5

formed by suitably bending sheet metal such as German silver, or brass, which may be plated, about the corded edge of the stringers as shown in the drawings, the sheet metal to one side of the plane of the anchoring portions, being further bent or folded to form a keeper portion 6 provided with an eye indicated at 7. The eye 7 is located partly in the upstanding flange 8 and partly in the body of the keeper portion, as clearly illustrated in Figure 2 of the drawings.

The second series 4 of the metallic elements are preferably formed from sheet metal by folding the same in the same manner as the series of eyed members but the bent-under-portions thereof are preferably formed so as to constitute a hook 9 which occupies a plane to one side of the anchoring portions 10 of the second series of elements, the hooks of course being located and projecting laterally so as to register and be interengageable with the eyes 7 in the other series of elements.

The two series of elements are adapted to be operated by a slider indicated generally at 11, of old and well-known construction and comprises essentially top and bottom plates 12 and 13 pinned or otherwise secured together as indicated at 14 to form two convergent guiding channels. The top and bottom plates are secured in the desired spaced apart relation by a block 15 which is preferably provided with a groove 16 for passage of the hooks 9.

Any suitable form of stop members may be provided at the upper and lower ends of the series of elements, headed pin 17 being shown at the upper end of the two stringers.

Each of the elements of both the series 3 and 4 has at its lower end a projection or tongue 18 extending from its bent-under portion in a direction parallel with the stringers 1. These projections are designed to fit into or engage with the element of the same series next below on the stringers thus preventing relative lateral movement. It will be seen, therefore, that the projections 18, serve to prevent lateral displacement of the elements in much the same manner as the hook 9 and eye 7 when in locked relation.

serve to prevent longitudinal displacement of the elements.

In operation when the slider 11 is pulled downwardly the elements are disengaged and when the slider is moved upwardly the elements are engaged by introduction of the hook members into the eye members in a manner that will be obvious. The hooks and eyes are so proportioned that when they are engaged it is impossible to disengage them by a direct lateral pull in opposite directions.

It will be apparent that the device is simple to manufacture, is compact, and presents a very narrow width of metal to the eye which is desirable from a manufacturing standpoint, and that the elements or fasteners, per se, are of a sturdy construction not likely to be bent or deformed in service and rendered inoperative. While the elements of the fastening device have been described as being formed out of bent metal, it will be understood that any suitable material can be used such as cast metal, etc.

It will of course be obvious that many changes may be made in the details of the construction without departure from the principles underlying this invention, and reference should therefore be made to the accompanying claims for an understanding of the scope of the invention.

Having thus described my invention, what I claim and desire to protect by Letters Patent is:

1. A multiple fastening device having two stringers, a series of interengageable elements having anchoring portions secured to each of the stringers, some of the interengageable elements having hook portions and other of the interengageable elements having eye portions, the interengageable elements being arranged on the stringers so that a hook portion is adapted to engage with an eye portion, said hook and eye portions being located to one side of the plane of their respective anchoring portions and being so constructed so that the hook portions and eye portions are engageable by edgewise convergent movement of the stringers.

2. A multiple fastening device having at least two stringers, a series of interengageable elements having anchoring portions secured to the stringers, some of the interengageable elements having hook portions and other of the interengageable elements having eye portions, the interengageable elements being so positioned on the stringers and so constructed that the hook portions of one stringer are engageable with eye portions on the other stringer, said hook portions and eye portions being offset from the plane of the anchoring portions, the hook portions being flat and extending in a direction from the stringer to which it is attached toward the other stringer.

3. A multiple fastener having at least two stringers, member having anchoring portions clamped on each of the stringers, some of said members having hook portions located at one side of the plane of the anchoring portions, and other of said members having recessed portions located at one side of the plane of the anchoring portions, said hook members and said eye members being so arranged on the stringers and so constructed that interengagement of the hooks with the eyes may be effected by convergent edgewise movement of the stringers.

4. A multiple fastening device having two stringers, interengageable elements having anchoring portions secured to each of the stringers, some of the elements having hook portions and other of the elements having eye portions, the elements being arranged on the stringers so that the hook portions of the elements of one stringer may be engaged with the eye portions of the elements of the other stringer, the hook portion and the eye portion of each of the elements being in a different plane from the anchoring portion of the respective elements, the hook portion being flat and extending in a direction from the stringer to which it is fastened toward the other stringer.

5. A separable fastener comprising a pair of stringers, two series of unlike elements, secured respectively to the adjacent edges of the two stringers, and having interengageable portions located and contacting in a plane offset from and parallel to the plane of the stringers, the interengageable portions being so constructed as to be engageable by convergent edgewise movement of the stringers.

6. A separable fastener comprising a pair of stringers, two series of unlike elements, secured respectively to the adjacent edges of the two stringers, and having interengageable portions located and contacting in a plane to one side of and parallel to the plane of the stringers, the interengaging portions being so constructed as to be engageable by the convergent edgewise movement of the stringers.

7. A fastener having a pair of stringers, elements secured to one stringer and cooperating elements secured to the other stringer, some of the elements of the first mentioned stringer each having an extending portion turned up at its end and having an eye formed in the extending portion, some of the elements of the second mentioned stringer each having a hook arranged to engage with the eye of the elements on the first mentioned stringer, said interengageable hooks and eyes being located in a plane offset from the plane of the stringers, said hooks and eyes being so constructed as to be engageable by convergent edgewise movement of the stringers.

8. A separable fastener consisting of two elements oppositely positioned on abutting stringers, the anchoring portions of each of said elements being formed to receive a stringer and extending from the edge of the stringer inwardly thereof to grasp a portion of the stringer therebetween, the interengaging portion of each element extending in a reverse manner relative to the anchoring portions and slightly turned up at its end, one of said elements having an eye engageable with a hook carried by the corresponding portion of the second element.

9. A separable fastener comprising two engageable elements, each element being formed in a reverse curve forming three substantially parallel portions in three separate planes, two of said portions of each element engaging a stringer forming an anchoring means, the third portion of each element extending beneath the plane of the stringer toward the other element and having means adapted to engage cooperating means on the other element.

10. A fastener consisting of two elements oppositely positioned on abutting stringers, each element extending oppositely on either side of its middle point, one extension being turned back over and clamped to a stringer and the other extension being turned back toward the opposing elements, the turned back extension of one element being adapted to engage with an eye carried by the corresponding extension of the other element.

11. A fastener comprising in combination a pair of stringers, a series of elements secured to the abutting edges of each stringer, the elements on one stringer having portions offset from the plane of the stringers and adapted to interlock with cooperating portions of the elements on the other stringer whereby longitudinal displacement of the elements is prevented, and means similarly positioned on each element consisting of a tongue extending in a direction parallel with the stringer adapted to engage the adjoining element on the same stringer whereby lateral displacement of the elements is prevented.

Signed at Waterbury, in the county of New Haven, and State of Connecticut, this seventh day of October, 1925.

DANIEL F. DALTON.
